JOHN T. HARRIGAN, OF PLAINFIELD, NEW JERSEY.

CIRCUIT CLOSER.

Application filed July 12, 1923. Serial No. 651,157.

My invention relates to circuit closers for jewel and money boxes.

An object of the invention is to provide a circuit closer adapted to sound an alarm when 5 the box with which the circuit closer is associated is lifted bodily from a support or when its lid is raised.

Other objects and advantages will be apparent from the following description, considered 10 in conjunction with the accompanying drawings, in which

Figure 1 is a perspective view showing an outer casing or box which is comprised in the device together with the alarm sounding 15 means housed herein, the lid of the outer case or box being raised.

Figure 2 is a view showing an inner case or box which is comprised in the device,

Figure 3 is a transverse vertical section 20 through the complete box with the lid of the outer case or box in raised position, and

Figure 4 is a diagrammatic view showing circuits which may be employed to operate the means for sounding an alarm.

25 My invention is designed primarily, although not necessarily, for the use of theatrical performers and others who have occasion to leave small articles of value such as jewelry, money and the like unguarded for 30 short intervals or in fact for any length of time.

In carrying out my invention, I provide an outer case or box 1 which preferably is formed of steel or other electrical conducting 35 metal of relatively great strength and which may comprise a substantially flat bottom 2, a pair of parallel end walls 3, a pair of parallel side walls 4, all formed integrally with one another, and a lid 5 which preferably is of box-like formation and includes a 40 depending continuous marginal flange attached by hinges 7 made of an electrical conducting material to one of the side walls 4 at the upper edge of the latter. An inner case 45 or box 8 comprises a bottom 9, a pair of parallel side walls 10 and a pair of parallel end walls 11, all made of a suitable material, such as metal and formed integrally one with the other or permanently secured to each other in 50 any suitable known manner. The length of the inner box 9 is slightly less than the distance between the inner faces of the end walls 3 so that the inner box 8 is adapted to rest within the outer box 1 and to span the space 55 between the end walls of the latter. However, the width of the inner box is considerably

less than that of the outer box so that a space will be provided between the side wall 4 to which the lid 5 is attached and the adjacent side wall of the inner box when the latter 60 is disposed within the outer box with the open side of the inner box uppermost and one side wall of the inner box in contiguous relation to the side of the outer box which is opposite that to which the lid 5 is attached.

65 This space is indicated at 12 in Figure 3 of the drawings and is closed at its upper end by a horizontally disposed rectangular plate 12 which is permanently secured along one longitudinal edge to the side wall of the 70 inner box which is proximate to the side wall of the outer box to which the lid 5 is attached or which may be formed integrally with the said side wall of the inner box. The length of the plate 12 is approximately the same as 75 that of the inner box and the width of the plate 12 is approximately equal to the distance between the side of the outer box to which the lid 5 is attached and the adjacent side of the inner box when the latter is disposed within 80 the outer box in the position illustrated in Figure 3.

The articles which are to be safeguarded 85 may be placed within the compartment which is provided within the inner box 8. The means for sounding an alarm when the lid 5 of the outer box is raised or when the outer box and the contents thereof are lifted bodily from a supporting surface includes an electric bell 13 which is disposed within the space 90 or compartment 12 and may be secured in any suitable known manner to one of the side walls 4, being insulated from the latter in any suitable known manner. A source of electric current supply shown as a battery 95 14 also is disposed within the compartment 12 and one side thereof is connected electrically by a conductor 15 to one side of the bell 13. An elongated switch arm 16 made of a material having electrical conducting qualities is secured at 17 against the inner face of the flange 6 of the lid of the outer box and depends within the space 12, being arranged to lie in a vertical plane when the lid 5 is closed and the box 1 rests upon a horizontal supporting 100 surface and to lie in a horizontal plane when the box 1 is supported in the manner just described and the lid 5 has been raised. The switch arm 16 is held in contact with the lid of the outer box by the fastening means 17. A spring contact member 19 is adapted 105 to cooperate with the movable switch arm 16

and is shown as being substantially Z-shaped, being formed to provide an upstanding intermediate portion having a horizontal attaching portion 20 at its lower end secured in any suitable known manner upon an insulating plate 18 which is secured upon the bottom 2. The upstanding intermediate portion of the spring contact member 19 has a horizontal portion 22 at its upper end extending in overlying relation to the free end portion of the switch arm 16 and constituting a stop against which the free end portion of the switch arm moves when the lid 5 has been fully raised, as illustrated in Figures 1 and 3. It is to be understood however, that the switch arm 16 will engage at its free end with the intermediate portion of the spring contact member 19 upon a slight upward movement of the lid 5 from fully closed position and will remain in contact with the intermediate portion of the spring contact member 19 during the continued upward movement of the lid toward the position illustrated in Figures 1 and 3. The spring contact member 19 is connected to the second side of the bell 13 by an electrical conductor 23 which may be attached at one of its ends to a binding post 21 which is carried by the contact member 19 and at its other end to the second side 30 of the bell.

The circuit for operating the bell which has been described so far is as follows: from one side of the battery 14 to the bell through the conductor 15, through the bell, along the conductor 23 to the spring contact member 19, from the other side of the battery 14 along the outer case 1, hinges 7 and lid 5 to the movable switch arm 16 and from the movable switch arm 16 to the spring contact member 19 when the lid has been raised to move the switch arm 16 into contact with the horizontal portion 22 of the spring contact member. The bell 13 will be sounded so long as the switch arm 16 is in contact with the spring contact member 19. When the lid is in closed position, the switch arm 16 is out of contact with the spring contact member 19 and the circuit is broken.

It is also desirable that the bell 13 shall be actuated when the outer box is lifted bodily. To this end, I provide a movable switch arm 24 which is made of a material having spring qualities and is attached adjacent to one of its ends to the bottom 2, as at 25, being disposed interiorly of the outer box as best seen in Figure 1. The switch arm 24 is connected electrically to one side of the battery 14 by means of a conductor 26. A substantially U-shaped contact member 27 having a pair of vertically spaced parallel arms 27^a and 27^b, respectively, is arranged with the arm 27^a secured upon a sheet of insulation 34 which in turn is secured upon the bottom 2, the arrangement being such that the switch arm 24 extends between the arms 27^a and 27^b.

The contact member 27 is connected by an electrical conductor 28 with the side of the bell 13 opposite that which is connected to the battery 14. Therefore, when the switch arm 24 is in contact with either of the arms 27^a or 27^b of the contact member 27, the bell 13 will be actuated. The circuit causing such operation of the bell is as follows: from the battery 14 to the bell along the conductor 15, from the bell to the contact member 27 along the conductor 28, from the contact member 27 through one of the arms 27^a or 27^b to the switch arm 24 and from the latter to the other side of the battery along the conductor 26. When the case 1 is resting in an upright position upon a flat supporting surface, the switch arm 24 is held out of contact with the contact member 27 by means of a slidable switch arm actuating member 29 which extends slidably through a vertical opening 30 in the bottom 2 and presses at its upper end against the lower face or side of the free end portion of the switch arm 24, thereby raising the latter from the arm 27^a to position between the arms 27^a and 27^b. The member 29 therefore functions in the manner of a push button and also serves as one of the four spaced apart supports or legs for the case 1 since the portion thereof which depends below the lower face of the bottom 2 is substantially the same as that of each of the remaining legs, the latter being designated 31 and being fixedly secured to the bottom 2 of the case. The legs 29-31 preferably are located at points adjacent to the corners of the bottom 2.

From the foregoing description of the various parts of the device, the operation thereof may be readily understood. When the lid 5 has been raised, the circuit through the switch arm 16 and the spring contact member 19 will be closed and the bell will be sounded. At this time, the lateral plate extension 12 will conceal the bell 13 and the parts operating the bell from view. It therefore will be difficult for a person unfamiliar with the construction of the device to stop the sounding of the bell by breaking the circuit. Warning will be given to interested persons that some unauthorized person has opened the box.

Should an attempt be made to remove the box bodily, the bell 13 will be operated as soon as the box has been lifted from the surface upon which it was supported as the spring arm 24 will be actuated because of the resiliency of the material of which it is formed to swing downwardly into contact with the arm 27^a of the stationary contact member 28 as soon as the movable supporting element 29 is permitted to move outwardly through the opening 30. This of course is when the box is lifted and the supporting surface upon which the box rests no longer acts as a stop to prevent outward movement of the slidable element 29.

Should the movable switch arm operating member 29 be pressed inwardly against the arm 27^b of the contact member 27 in an endeavor to stop the sounding of the alarm, the circuit through the contact member 27 and the switch arm will be closed to insure further sounding of the alarm.

The case 1 and the lid therefor may be provided with cooperative fastening elements of 10 any suitable known construction, such as the cooperative locking elements indicated respectively at 32 and 33.

Obviously, my invention is susceptible of embodiment in forms other than that illustrated in the accompanying drawing and I therefore consider as my own all modifications and adaptations of the form of the device herein described which fairly fall within the scope of the appended claim.

Having thus described the invention, what I claim is:—

In combination a portable base having a plurality of fixed supporting feet upon its

under face, a U-shaped contact member supported upon the inner face of the base with 25 its parallel legs arranged horizontally and having electrical connection with one terminal of a source of electrical energy, a resilient switch arm fixed to the base and having electrical connection with the other terminal of the source of electrical energy, the switch arm being disposed between the parallel legs of the U-shaped member and normally urged towards the lower one to 30 complete an electrical circuit, and a vertically movable supporting foot attached to the free end of the switch arm and normally holding the latter in a position where it will not contact with the U-shaped member while the portable base is at rest upon a support, the 35 switch arm being operable to engage the upper horizontal leg of the U-shaped member to complete the electrical circuit in the event the movable foot is pushed manually upwardly.

JOHN T. HARRIGAN.
